UNITED STATES PATENT OFFICE.

HERMAN C. KUHLMAN, OF CLEVELAND, OHIO, ASSIGNOR OF ONE-THIRD TO FREDRICK KESTNER AND ONE-THIRD TO MARTIN CALLAHAN, BOTH OF CLEVELAND, OHIO.

AUTOMATIC MAIL CATCHER AND DELIVERER.

1,072,129.

Specification of Letters Patent.

Patented Sept. 2, 1913.

Application filed July 22, 1911. Serial No. 639,988.

To all whom it may concern:

Be it known that I, HERMAN C. KUHLMAN, a citizen of the United States, residing at Cleveland, in the county of Cuyahoga and State of Ohio, have invented certain new and useful Improvements in Automatic Mail Catchers and Deliverers; and I do hereby declare the following to be a full, clear, and exact description of the invention, such as will enable others skilled in the art to which it pertains to make and use the same.

This invention relates to mechanisms for delivering mail pouches and packages both from and to a moving car; said delivery being accomplished in a safe and positive manner to and from the car without liability to injure either the mail matter or any person or persons employed in connection therewith.

The object of this invention is to provide a mechanism embodied within a mail car operated therefrom hence being under the control of the mail agents in the car, for the purpose of setting the mechanism for the delivery of any mail matter to a station along the way and to collect any mail matter for transit from said station or stations, the entire mechanism being under the control of the mail car employees or in other words the postal employees.

A still further object of this invention is to obviate any dangerous conditions and to attain simplicity and ease of operation and not necessitating a knowledge of mechanics for setting or operating the mechanism.

Still another object of this invention is the providing for the positive and safe delivery of the mail to and from the car or to and from the station regardless of the speed of the train while passing the station.

With the above and other objects in view my invention consists in the parts and combination of parts all of which will be hereininafter fully set forth and claimed.

In the drawings, Figure I, is perspective view of my device. Fig. II, is a cross sectional view taken through a car and its delivering mechanism and also through the station delivering device showing in part some of the setting mechanism. This view shows the device delivering the mail to the station from the car in operation and at the same time the mechanism set for the delivering of the mail from the station to the

car. Fig. III, is a longitudinal vertical section taken through that portion of a car contiguous to the door illustrating a system of cables or chains and the manner of setting the apparatus by means of the guard or shield. Fig. IV, is a plan view looking at the bottom of the car with some parts removed showing more clearly certain parts of the setting mechanism not clearly brought out in either of the other figures. Figs. V, VI, VII, VIII and IX, are detached views showing enlarged details of construction of the setting mechanism.

In the drawings I have illustrated a system of setting device and the details of construction as I consider them best adapted for performing their different functions while at the same time attaining economy in construction, but I do not wish to be limited or confined to the same inasmuch as they may be altered or modified according to conditions or requirements.

In the drawings, 1, represents a car, usually a properly fitted mail car which may have either swinging or sliding doors, (I have illustrated swinging doors).

2 represents a trough shaped chute attached, one at either side of the car if necessary, this chute or delivery device 2 is accessible from the inside of the car through a trap door 3 opening upward from the floor of the car through which the mail pouch or matter is introduced. A horizontally swinging and vertically hinged door 4 is provided for closing the delivery mouth of the chute and is kept in locked and closed position by means of swinging latches 5-5 which engage keepers 6 attached to the door 4 at either side of the same and it is by the release of these latches 5-5 and positively operated arms 7 (see Figs. II and IV) that the door 4 is opened. The arms 7-7 are in turn secured to cables or chains 8-8 which pass over sheaves 8-8' and from them to pivoted levers 9-9. The pivoted levers 9-9 having at their ends vertically hinged engaging arms 9'-9'- (see more clearly Fig. VII) these arms 9'-9'- are projected through a medium of a crank lever 10 operated by chain or cable 10' thus one of the arms 9' being made to project outward from the car and comes in contact with a projection 9'' (see Figs. I and II) attached to the station delivering mechanism which

throws the lever 9 in such a direction as to force the door 4 open allowing the mail matter to slip from the chute 2 into a trough 2' located along the line of the track and in juxtaposition to the passing mouth of the chute 2. This trough 2' retains the pouch or mail matter, keeps it from injury and from being thrown beneath the car and hence should be made of such length (see Fig. I) as to provide for this.

The above sets forth my preferred mechanism and its operation for delivery of the mail matter from the car to a by-station without the stoppage of the train and regardless of the speed of travel. Its simplicity is obvious.

Now taking up the mechanism whereby the mail is delivered to the car while the same is in motion it is described as follows:

20 The above mechanism embodies a delivery device located on the station platform and in juxtaposition to the track and on either side of the said track as found convenient or necessary. This mechanism comprises a 25 swinging post 11 mounted so as to be swung into or out of operative position and locked in either position by means of a bolt 11' and a lever 11'' or some such device whereby the post 11 may be swung by means of a lever 30 11'' into either position. The manner of mounting the post 11 is immaterial providing it allows the apparatus to be shifted in operative or inoperative position and locked. Mounted on the upper end of the post 11 is 35 an elongated head 12 formed with a recess 12' for the reception of a piston or plunger 12'' and its projection spring 13 which acts to keep said plunger or piston projecting from the head and by means of rods 14—14 40 one on either side and attached to the back end of the piston 12'' as at 14' and to the lower end of pivoted arms 15—15 as at 15' in turn attached to the projector 16 to keep said projector at rest (see Fig. I) in which 45 position the mail matter or pouch is placed in said projector which is the normal condition or position of this mechanism. The forward end of the piston or plunger 12'' may be provided with a friction roller 17 50 which is adapted to be engaged by either of the two trips or cams 18—18, depending in which direction the train is traveling, either of which is projected from the car, (see Figs. I, II and IV) which is accomplished 55 through the medium of sliding projectors 19—19, either of which may be set into operation and thus as the friction roller 17 is engaged by a cam or tripper 18 the piston or plunger 12'' is forced backward against 60 the tension of the spring 13 carrying with it the rods 14—14, pivoted to the short end of the arms 15—15, the long end of said arms having a greater throw and hence a greater speed throws the projector 16 toward the 65 door of the car which is open, and projects

the mail matter into the car against the shield or guard 20 which may be formed of heavy flexible matter such as duck or canvas and with suitable supporting frames, the same being hinged as at 20' so as to be folded up out of the way when not in use. This shield or guard 20 may be supported when in operative position by a guy rope 20'' if desired or found necessary, one of which may be placed at either side at the upper 75 back corners.

In case swinging doors are employed on the car I so construct them as to swing inwardly and provide suitable apparatus such as springs to tend to open them and to hold them open, they being locked shut by means of a spring pressed bolt 21 (see Figs. II III and VIII) which engage the upper meeting edges of the doors thus when said bolt is raised and disengaged from the doors 80 the doors fly open in position to receive the mail pouch from the projector.

In order to facilitate the setting of the different trips or cams 18 I have connected them severally with a series or system of 90 cables or chains 10' which operates the arm 9' of the lever 9 and in which 21' operates the spring pressed bolt 21 for unlocking the doors, cables or chains 22 which operate the trips or cams 18—18 through the sliding 95 projectors 19—19 and cables 23 which operate to release the latches 5 (see Fig. III) all of which are operated through the lowering into position of the guard or shield 20. A hook 24 being provided at either side for 100 engaging said guard or shield 20 thus when said guard or shield is lowered the said cables or chains bring into action and set the different apparatus according to the direction of the travel of the train.

In Fig. V, of the drawings I have illustrated in enlarged form the catches 5—5 with cables 8—8 attached and connected together which lock the door 4 of the chute 2. In Fig. VI, I have illustrated a construction 110 of trip or cam 18 illustrating it with a short arm provided with a spring 18' for returning it to its normal position.

Fig. VII illustrates a construction of the trip lever 9 which operates to open the door 115 4 and the manner of throwing out the hinged arm of the same as is hereinabove set forth. In Figs. VIII and IX I have shown in elevation and top plan view the door bolt with cables attached for operating the same.

From the above description taken in connection with the drawings it will be seen that I have provided a simple, positive and safe apparatus for the delivery of mail to or from a car while at the same time providing an apparatus which will operate perfectly at any rate of train speed and have also provided a mechanism which cannot be disturbed through the action of the weather or climate. It being understood of course 130

that the posts may be duplicated at either side of the car or track if found convenient or necessary.

I have set forth and described what I have at the present time found to be best adaptable to this invention but I do not wish to be limited to the exact construction of parts as they may be greatly modified without departing from this invention.

10 What I claim is:

1. A mail pouch delivery apparatus comprising a stationary pouch support mounted in juxtaposition to the line of way, and adapted to be set into operation by the passing of a car, in combination with a guard device located within the car, said guard device being connected to the mechanism for operating the device for delivering the mail to the car and the device for delivering the mail from the car.

2. A mail receiving and delivering device comprising the combination of a stationary delivery support mounted in juxtaposition to the line of travel of a passing car, means mounted on said passing car for setting into operation the stationary delivery support with a receiving guard mounted in said passing car, said guard adapted when adjusted in position to set into operative position the mechanism for delivering the mail from the passing car to the station.

3. A mail delivery apparatus comprising a stationary support, a horizontal piston mounted in said support and being spring pressed, a pivotally mounted, vertically swinging projector mounted on said support and connected to said spring pressed piston, the whole being located in juxtaposition to the line of travel of a car to which mail is to be delivered by said apparatus, in combination with means carried by said car for operating said apparatus, substantially as set forth.

4. A mail receiving and delivering device comprising the combination of a stationary delivery support mounted in juxtaposition to the line of travel of a passing car, a horizontally mounted plunger located in said support, one end of said plunger being connected to rods which in turn are connected to a swinging delivery arm, the opposite end of said plunger being adapted to come into contact with means on the passing car for operating said plunger.

5. A mail receiving and delivering device comprising a stationary delivery support mounted in juxtaposition to the line of travel of a passing car, a plunger mounted horizontally in said support, one end of said plunger being connected to rods which in turn are connected to the lower end of a pivotally mounted, vertically swinging delivery arm, the opposite end of said plunger adapted to come into contact with an op-

erating mechanism located on the passing car, said plunger also being spring pressed substantially as and for the purpose set forth.

6. A mail delivery and receiving device comprising a stationary delivery support located in juxtaposition to the line of travel of a passing car, a plunger mounted horizontally in said support one end of said plunger being connected to rods which in turn are connected to the lower end of a pivotally mounted delivery arm, the opposite end of said plunger adapted to come into contact with an operating mechanism located on the passing car, the location of said plunger and operating mechanism being approximately level with the floor of the car substantially as and for the purpose set forth.

7. A mail delivering and receiving device comprising the combination of a stationary delivery support located in juxtaposition to the line of travel of a passing car, a horizontally mounted plunger mounted in said support, said plunger adapted to operate a swinging delivery arm when contact is made between it and an operating mechanism located on the passing car, with a receiving guard located in the passing car, said guard adapted to set into operative position all operative mechanisms located on the passing car.

8. A mail delivering and receiving device comprising a car, a receiving guard located within said car; means connected to said guard for placing into operative position all operative mechanisms located on said car; said operative mechanisms comprising a receptacle located beneath the car body, said receptacle having a door leading from it to the interior of the car and another door leading from it to the exterior of the car; triggers located on the outside of said car and adapted to come in contact with a plunger of a stationary delivery support located in juxtaposition to the line of travel of said car; triggers adapted to come into contact with a projecting portion of the stationary delivery support for releasing the outer door of said receptacle all substantially as and for the purpose set forth.

9. A mail delivering and receiving device comprising a car a receptacle located beneath the body of said car said receptacle having a door communicating with the interior of said car and another door communicating with the exterior of said car, triggers mounted on said car with means connecting said triggers with said outer door latch, said triggers adapted to come into contact with a projection located on the stationary delivery support located in juxtaposition to the line of travel of said car, said support having a horizontally sliding plunger mounted therein, one end of said

plunger connected to rods which in turn are connected to the lower end of a vertically swinging pivotally mounted delivery arm the other end of said plunger adapted to come into contact with an operating trip-
5 per located on said car, a receiving guard located within said car, said guard, when placed into position, adapted to bring all operative parts and mechanisms into op-

erative position all substantially as and for 10 the purpose set forth.

Signed at Cleveland in the county of Cuyahoga and State of Ohio this 1st day July 1911.

HERMAN C. KUHLMAN.
